CARRIAGE DRIVING AND HAMMER
RETURNING MECHANISM

Frank Spaloss, Hoboken, N. J., assignor, by mesne assignments, to Ralph C. Coxhead Corporation, New York, N. Y., a corporation of Delaware

Application July 7, 1931, Serial No. 549,210

9 Claims. (Cl. 197—49)

This invention relates to typewriting machines and more particularly to improved power means for driving the carriage and for restoring the printing hammer against the action of its actuating spring.

An object of the invention is to provide a device, for the above stated purpose, with a minimum of parts so that it may be manufactured economically and operated efficiently.

Another object of the invention is to provide a power means the strength of which does not vary but is always the same at each operation thereof.

In carrying out the invention the power device comprises a spring connected by suitable means with the carriage and the printing hammer to assist in driving the carriage and to return the hammer after each printing operation.

It is a feature of the invention to energize the spring at each letterspace movement of the carriage to have the action of the spring always the same on the carriage and also to maintain at a minimum the power of the spring so as not to overburden the carriage escapement mechanism with which the power means is associated.

The storing of the energy in the spring is effected by means under the control of the key levers so that its operation is effected at each actuation of any one of the key levers. Said means includes an electro-magnet or solenoid connected through a reciprocatory device with said spring.

In the present form of the invention the reciprocatory device includes a lever, to which is connected the spring, and upon which is pivotally supported a pawl which co-operates with a ratchet wheel connected with the escapement wheel to assist in driving the latter in a positive direction, said escapement wheel being connected in the usual manner through a dog carrying lever with the printing hammer.

Another feature of the invention relates to carriage release mechanism which is simple and compact in construction and is readily accessible.

Other features and advantages will hereinafter appear.

In the drawings which form part of the specification,

Fig. 1 is a sectional side view of the machine; Fig. 2 is a sectional top plan view of the machine, some of the parts being broken away and others being omitted;

Fig. 3 is a rear view of the machine, parts being broken away;

Fig. 3a is a diagram of the electric circuit;

Fig. 4 is a fragmentary rear view showing the solenoid operating to cock or set the power means;

Fig. 5 is a vertical section through the parts carried by the escapement shaft;

Fig. 6 is an operating view showing the carriage release pawl disengaged;

Fig. 7 is a rear view of Fig. 6; and

Fig. 8 is a rear view of the pinion sleeve showing its connection with the escapement shaft.

Similar characters refer to similar parts throughout the several views.

The invention is shown applied to a Varityper writing machine which includes a main frame 20 to which is secured a track 21 upon which a carriage 22 is mounted to travel back and forth 15 transversely of the machine. The carriage is provided with a bar 23 which co-operates with the track 21 through anti-friction rollers or balls 24 to guide said carriage. The carriage is further guided by a bar 25 at its upper end co-oper- 20 ating with a roller 27 mounted on the main frame 20.

The carriage is urged in a letter feed direction by a carriage propelling means or spring drum 30 (Figs. 2 and 3) rotatably supported by a shaft 31 25 on the main frame 20; the spring drum being connected to the carriage by a strap or draw band 32. Letter feed movements of the carriage are effected by escapement mechanism, indicated generally by the numeral 33, which is actuated at each opera- 30 tion of the key levers 34.

The escapement mechanism includes a sleeve 35 slidably supported on a shaft 36 supported in a rear cross-bar 37 of the main frame and a lug 38 of said frame. The sleeve 35 has secured thereto 35 three pinions 39, 40 and 41 of different diameters to effect variable spacing of the carriage in a manner described in the application of Frank H. Trego, Serial No. 361,899, filed May 10, 1929. Any one of the pinions may be engaged by a rack 42 40 carried by two arms 43 pivotally supported on studs 44 on carriage ends 45. The sleeve 35 has a key 46 (Figs. 5 and 8) secured thereto which engages in a groove 47 of the shaft 36 to rotate the shaft 36. 45

An escapement wheel 48 is rotatively supported on the escapement shaft 36 and has secured thereto a ratchet wheel 49 by screws 50. The ratchet wheel 49 is engaged by a pawl 51 pivoted by a screw 52 on an arm 53 secured to a hub 54 50 55. The latter being fastened to the shaft 36 by a pin 55. Thus by this connection the escapement wheel is connected to be rotated by the carriage through the medium of the shaft 36 in a letter space direction. Said escapement wheel is nor- 55

mally held against rotation by a loose dog 56 pivoted by a stud 57 on a lever 58 and urged towards the escapement wheel by a spring 56a. The lever 58 is pivoted on the escapement shaft 36, and is urged downward by the escapement wheel through the pawl 56, the downward movement of the lever 58 being limited by a stop 59 of a fixed bracket 60 secured to the rear bar 37 of the machine frame. While the carriage is being returned the pawl 51 rides freely over the teeth of the ratchet 49 against the action of a spring 61 connected between an ear 62 of the pawl 51 and a pin 63 on the arm 53. A spring pressed pawl 64 (Fig. 3) prevents backward rotation of the escapement wheel.

To actuate the escapement mechanism 33 and thus feed the carriage at each printing operation, the key-levers 34 when actuated about fulcrums 65, engage a universal bar 66 of a frame 67 to swing the latter about a fulcrum 68. An arm 69 of the frame 67, when the latter is actuated, swings downwardly to actuate a dog rocker 70, about a pivot 70a, through the medium of a set screw 71 on the arm 69 and engaging a tail 72 of the dog rocker to carry a fixed dog 73 into engagement with the teeth of the escapement wheel 48.

The dog rocker 70 is provided with an arm 74 having a slot 75 into which extends a pin 76 from the loose dog 56, whereby the loose dog is swung out of engagement of the escapement wheel; the loose dog carrying lever 58 being connected to a printing hammer 77 by means of a stud 78 to be actuated thereby during a printing operation of said hammer which is actuated in a manner hereinafter described. As the pin 76 travels upwardly out of the slot 75 the dog 56 is guided into the path of the next succeeding tooth of the escapement wheel under the influence of the spring 56a, the upward movement of the pawl being limited by a stop 79. Subsequently the dog rocker 70 is brought back to normal upon the return of the arm 69 to disengage the dog 73 from the escapement wheel, whereupon the escapement parts and the printing hammer 77 are restored to normal through the action of the escapement wheel 48 on the loose dog 56.

The printing instrumentalities include a type carrier or shuttle 80 having types 81 with which a head 82 of the hammer 77 co-operates to print against an interposed work sheet 83, the work sheet being fed up and down by suitable feed rollers 84 and 85 supported on the carriage 22. The type shuttle 80 is curved to conform with a cylindrical anvil 86 by which it is carried through the medium of a thin flange 87 extending through a slot 88 in said anvil.

To actuate the type shuttle 80 the flange 87 has connected thereto a lever 89 secured to a sleeve 90 to rotate about the shaft 91; the sleeve 90 being supported on a bar 92, of the main frame, on which it is maintained by a screw 93 engaging a flange 94 at the lower end of the said sleeve.

The shuttle actuating lever 89 may be actuated, from a central position, in opposite directions by either of two arms 95, about the axis of the shaft 91, said arms being actuated, one at a time, in a manner hereinafter described to carry the selected type of the shuttle 80 to the printing point, the types being accurately positioned by means of indexing pins 96 operable by the key levers 34 to project their upper ends into the path of the shuttle lever 89 to arrest the latter. Subsequently the hammer is actuated by a spring 96 under

the control of the escapement mechanism, said hammer being secured to a shaft 97 supported by pivot screws 98 on the main frame 20.

Each of the arms 95 may operate the shuttle actuating lever 89 through the medium of a resiliently supported slide 99 which may be like that disclosed in the application of Frank H. Trego, Serial No. 412,651, filed December 19, 1929, to facilitate a movement of said arms after the lever 89 has been arrested. Each arm forms part of a frame 97, each frame being supported to swing about a pivot 99a on a fixed bracket 99. Each frame 97 also includes a bar 100 extending towards the middle of the machine and over the key lever 34 at one side of the middle of the machine, so that if any one of the key levers is operated the associated one of the frames 95 is actuated thereby against the action of a return spring 101. The upper end of the arm 95 is thus swung rearwardly to actuate the lever 89 and shuttle 80 to select the type as above described.

After the type shuttle is arrested in its operated position the release of the printing hammer is effected from the escapement wheel by the actuation of the dog rocker 70 as previously described. It is then actuated by the spring 96 connected thereto.

The letter spacing of the carriage may be changed in accordance with the various sizes of the types of different shuttles which may be used in the machine, by shifting the sleeve 35 axially on the shaft to cause any one of the pinions 39, 40 or 41 to co-operate with the rack 42. To set the sleeve or pinion element 35 there may be provided suitable selecting mechanism which may be like that disclosed in the application of Frank H. Trego, Serial No. 361,899, now Patent No. 1,918,299, July 18, 1933, which mechanism includes a lever 102 (Fig. 2) pivoted by a stud 103 on the machine frame and having two pins 104 engaging in a groove 105 of the sleeve 35.

Novel means is provided whereby the rack 42 may be left in engagement with the active pinion when the release of the carriage is effected. To this end a thrust rod or plunger 106 (Figs. 1 and 5) is slidably supported on the hub 54 at the end of the escapement shaft 36. The inner end of said plunger is provided with an annular cam 107 to engage an inclined portion 108 on the ear 62 of the pawl 51 so that when the plunger 106 is pushed inwardly from the normal position in Fig. 5 to the position in Fig. 6 it moves the pawl about the pivot 52, in any position which it may occupy about the axis of the escapement shaft, to disengage said pawl from the ratchet as in Figs. 6 and 7 where the ear 62 rides on a dwell 107a of the cam 107. Thus it will be understood that the carriage may be released without disengaging the rack which would otherwise disturb the margin or vertical alignment of the typing.

The carriage releasing mechanism connected to actuate the plunger 106 may be like that disclosed in the application of Frank H. Trego, Serial No. 384,603, filed Aug. 9, 1929. Said mechanism includes two carriage release levers 110 supported at opposite ends of the carriage by a shaft 111 supported in the carriage ends 45.

Each release lever 110 is actuatable in a clockwise direction about the shaft 111 (Fig. 1) against the action of a return spring (not shown). The lower end of each release lever has a slot 112 (Fig. 1) into which projects a pin 113 from an arm 114 pivotally supported on a hub 115 of the rack supporting arms 43. The arms 114 have secured thereto a bar 116, extending lengthwise

of the carriage. Said bar 116 is swung in a 5 counterclockwise direction (Fig. 1) upon the actuation of either release lever 110 and engages the end of an arm 117 secured to a shaft 118. The arm 117 is located near the middle of the machine so that it may always be engaged by the bar 116 in any position of the carriage. The shaft 118 is supported by a bracket 119 and has another arm 120 secured thereto, the free end of 10 said arm 120 being connected to said plunger 106 to actuate the latter. A spring 121 is coiled about the shaft 118 and acts on the arm 117 to return it to normal.

The dog carrying lever 58 is provided with a 15 hub 122 (Fig. 5) extending into a cavity 123 in the escapement wheel 48 to provide a compact arrangement of the parts. It is desirable that the escapement wheel have a broad bearing on the escapement shaft so it is provided with a hub 124 and to further keep the mechanism as compact as possible the hub 54 of the pawl carrying arm 53 is provided with a cavity into which the hub of the escapement wheel extends.

It should be understood that by mounting the 20 release element 106, pawl 51, ratchet 49 and escapement wheel 48 on that portion of the escapement shaft extending outside of the machine frame, or in other words behind the bar 37 thereof, the parts are readily assembled and are accessible for the purpose of repair, the heretofore necessity of removing the typewriter carriage being thus eliminated.

The novel means which assists in returning the printing hammer includes a spring 125 (Fig. 3) 25 one end of which is connected to an adjustable screw 126 on a bracket 127 secured to the rear bar 37 of the machine frame by screws 128. The other end of the spring is connected to a lever 129 pivoted by a stud 130 on said bracket 127, the spring tending to rock the lever 129 in a clockwise direction to rotate the ratchet 49 and the escapement wheel 48 secured thereto in the same direction through the medium of a pawl 131 supported on the shoulder of a headed stud or screw 40 132, the pawl 131 being held in contact with the ratchet 49 by a spring 133.

It will be understood that whenever the lever 129 is actuated in counterclockwise direction, (Fig. 3) the pawl 131 is cocked as in Fig. 4 against the 45 action of the actuating spring, said pawl snapping over one of the teeth of the ratchet 49. Thus the spring 125 is energized at each actuation of the lever 129 in a counter clockwise direction which occurs at each letter space movement of the carriage after the printing operation and is caused 50 by means hereinafter described, under the control of the key levers 34. After the reciprocatory means including the lever 129, pawl 131 and spring 125, has been cocked it is released and rotates the escapement wheel to restore the printing hammer 71, against the action of its spring 96, through the medium of the dog 56 and the dog supporting lever 58.

To actuate the lever 129 and thus increase the 55 strength of the spring 125 there is provided an electro-magnet or solenoid 135 held on the rear bar 37 of the machine frame by straps 136, said straps being secured by screws 137 and 138. Said solenoid when energized, as hereinafter described, 60 sucks in a plunger 139 to draw on a link 140 pivotally connected thereto by a pin 141. The other end of the link 140 is connected to the lower end of the lever 129, by a shouldered screw 142, to actuate the lever 129 in a clockwise direction when 65 the solenoid is energized.

To limit the movement of the plunger 139 and its connected parts when actuated by solenoid 135 (Fig. 4) the lever 129 has bent off therefrom a lip 143 to engage a stop 144 secured to the bar 37 of the main frame, said stop having also a lip 145 with a piece 146 of leather or rubber thereon to be engaged by the lip 143 of the lever 129. To increase the efficiency of the solenoid it has inserted in one end thereof a core 147 secured to a bracket 148 supported on the strap 136, the core 10 having a screw portion 149, extending freely through said bracket, and upon which is threaded one or more nuts 150 to hold the plug on said bracket.

The operation of the solenoid is effected by a 15 normally open switch 155 (Fig. 3) which may be closed at the proper time by any one of the key levers 34 to cause an electric current to flow from a source of supply 156 (Fig. 3a) through conductor 157, main switch 158, conductor 159, solenoid 20 135, conductor 160, switch 155, conductor 161 to ground 162. When the actuation of the solenoid is thus effected the escapement actuating mechanism including the pawl 131 is cocked thereby as above described.

The switch 155 includes a fixed contact 163 to which is connected the conductor 161, said contact being resiliently supported by a flat spring 164 on a block 165 of insulating material secured to bottom of the bar 37 of the main frame, by screws 30 166, the contact spring 164 being secured to the block 165 by a screw 167. The switch further includes a movable contact 168 to which is secured the conductor 160. The contact 168 is secured to a block 169 of insulating material fastened to a 35 metal arm 170 pivoted by a pin 171 on the block 165. A spring 172, interposed between the block 165 and the arm 170, normally holds the switch 155 open, the pivoted element of said switch, comprising the parts 169 and 170, being arrested by 40 the head 173 of a set screw 174 threaded into the block 169 and held in its adjusted position by a nut 175, said head engaging a finger 176 secured to the arm 69 of the universal for frame 67.

To close the switch 155 the finger 176 presses 45 downwardly on the screw 173, whenever the universal frame 67 is operated by the key levers 34 as above described, to swing the pivoted switch element downwardly against the action of the spring 172, to cause the contact 168 to engage the 50 contact 163 and thus close the switch 155 whereupon the solenoid 135 operates to cock the pawl 131 against the action of the spring 125 as previously described.

It will be understood that as long as the key 55 lever is depressed the solenoid remains energized and consequently the pawl 131 is held cocked until after the printing operation. Immediately upon the return of the key lever the switch 155 is opened by the spring 172 whereupon the spring 60 125 becomes active to drive the carriage through the medium of the pawl 131 and ratchet 49, and also to return the hammer 71 against the action of its spring 96.

Briefly the operation of the device is as follows: Upon the depression of any one of the key 65 levers 34 the rear end swings upwardly to actuate the universal bar frame 67, about the pivots 68, to move the rear end thereof downwardly to actuate the escapement through the medium of the 70 dog rocker 10 which releases the loose dog 56 from the escapement wheel 48. The spring 96 then becomes effective to actuate the hammer 71, which is connected to the frame 58 by the pin 78, to printing position.

During the latter part of the actuation of the universal frame 67 the arm 176 thereon closes the switch 155 to effect the operation of the solenoid 135 which through the link 140 and lever 129 stretches the spring to energize it, the parts being arrested by the stop 146 with which the lever 129 engages.

5 The switch 168 is then opened by the spring 172 during the early part of the return stroke of the 10 operated key lever whereupon the spring 125 becomes effective through the lever 129, pawl 131 and ratchet 49 to rotate the escapement wheel 48 and return the frame 58 through the loose dog 56 after the latter has reengaged the escapement 15 wheel. Since the frame 58 is connected with the hammer 71 the latter is returned to normal, by said frame, against the action of the hammer 20 operating spring 96.

Thus the spring 125 of this device, which assists the spring drum 30 in feeding the carriage and returning the hammer 71, is energized at 25 each letter space movement of the carriage or at each actuation of any one of the key levers.

While certain preferred embodiments of the 25 invention have been shown and described, it should be understood that changes in the form, arrangement, proportions, sizes and details thereof may be made without departing from the scope of the invention as defined in the appended 30 claims.

I claim:

1. In a typewriting machine, the combination of a carriage, carriage propelling means, escapement mechanism for the carriage, said escapement mechanism including a shaft, an escapement wheel on said shaft, a ratchet wheel on said escapement wheel, a pawl on said shaft to engage said ratchet to form a one way driving connection between the shaft and the escapement wheel; a second pawl to engage said ratchet to assist in feeding the carriage, means including a spring to drive the second pawl, key levers, and means under the control of the key levers to energize the spring at the actuation of 45 any one of the key levers.

2. In a typewriting machine, the combination of printing instrumentalities including two elements, key-levers, means operable by the key-levers to effect the operation of one of the printing elements against the other to print on an interposed work sheet, means to return the operable printing element to normal, the returning means including a ratchet wheel, means connecting the ratchet wheel with the operable element, a lever, 50 means to pivotally support said lever at the side of said wheel, a pawl supported at the upper end of said lever and extending over said ratchet wheel and operable by said lever to engage said wheel to actuate it, a spring connected to said 55 lever to actuate the latter, an electric device located at the opposite side of the ratchet wheel, and a link extending under said ratchet wheel and connecting the electric device to said lever so that the latter may be actuated by said electric 60 device to energize said spring.

3. In a typewriting machine, the combination of printing instrumentalities including two elements, means to actuate one of said elements to print against the other element, a main frame, a 70 carriage to travel on said main frame, escapement mechanism including a shaft supported on said main frame, means connecting said shaft to be rotated by said carriage, means to propel said carriage, an escapement wheel rotatably supported on said shaft, a ratchet wheel secured to

said escapement wheel, means operable by the escapement wheel to restore the actuatable printing element to normal, a pawl carried by said shaft to cooperate with said ratchet to form a one way driving connection between the carriage and the escapement wheel, and auxiliary means acting on said ratchet wheel to assist in rotating the escapement wheel to restore the actuatable printing element.

4. In a typewriting machine, the combination 10 of printing instrumentalities including two elements, means to actuate one of said elements to print against the other element, a main frame, a carriage to travel on said main frame, escapement mechanism including an escapement wheel, 15 a ratchet secured to the escapement wheel, means including a pawl connected to and operable by said carriage, said pawl cooperating with said ratchet to form a one way driving connection between the carriage and said escapement wheel, 20 means connecting the escapement wheel with the actuatable printing element to return the latter to normal, and means to engage said ratchet to actuate the escapement wheel in effecting the 25 return of the actuatable printing element.

5. In a typewriting machine, the combination 30 of printing instrumentalities including two elements, means to actuate one of said elements to print against the other element, a main frame, a carriage to travel on said main frame, escapement mechanism including an escapement wheel, 35 a ratchet secured to the escapement wheel, means including a pawl connected to and operable by said carriage, said pawl cooperating with said ratchet to form a one way driving connection between the carriage and said escapement wheel, 40 means connecting the escapement wheel with the actuatable printing element to return the latter to normal, driving means including an element to engage said ratchet to effect the return of the 45 actuatable printing element, key levers, and means operable by said key levers to effect the energization of said driving means at each actuation of a key lever.

6. In a typewriting machine, the combination 45 of printing instrumentalities including two elements, means to actuate one of said elements to print against the other element, a main frame, a carriage to travel on said main frame, escapement mechanism including an escapement wheel, 50 a ratchet secured to the escapement wheel, means including a pawl connected to and operable by said carriage, said pawl cooperating with said ratchet to form a one way driving connection between the carriage and said escapement wheel, 55 means connecting the escapement wheel with the actuatable printing element to return the latter to normal, driving means including an element to engage said ratchet to effect the return of the 60 actuatable printing element, key levers, an electrically operable device, a normally open switch connected in circuit with said device, and means operable by any one of said key levers to close said switch to render said device effective to effect the energization of the driving means.

7. In a typewriting machine, the combination 65 of a carriage, escapement mechanism therefor, key levers, a printing hammer under the control of said key levers, said escapement including a shaft, an escapement wheel on said shaft, a loose 70 dog, a supporting lever for the loose dog, said dog cooperating with said escapement wheel, the supporting lever being connected with said hammer, a ratchet secured to the escapement wheel, and a pawl on said shaft to engage said ratchet 75

5 to form a one way driving connection between the escapement wheel and said shaft, means including an actuating pawl engaging said ratchet to rotate the escapement wheel and thus actuate the pawl carrying arm to return the hammer, and means operable by the key levers at each actuation of any one of them to effect the cocking of said actuating pawl.

8. In a typewriting machine, the combination 10 of a carriage, escapement mechanism therefor, said escapement mechanism including a ratchet, key levers, a printing hammer under the control of said key levers, said escapement including an escapement wheel, a loose dog, and a supporting 15 lever for the loose dog, means connecting the supporting lever of said escapement with said hammer, a lever of the first order, means including a pawl operable by the lever of the first order to actuate the escapement wheel through said 20 ratchet, a spring attached to one end of said lever to return the hammer, power means connected to the other end of said lever of the first

order and means operable by the key levers to effect the cocking of said lever of the first order against the action of its spring by said power means at each actuation of any one of the key levers.

9. In a typewriting machine, the combination 10 of a carriage, key levers, means operable by said key levers to effect the feed of the carriage, said means including a rack on said carriage, a shaft, a pinion to engage said rack and connected to 15 rotate with said shaft, an escapement wheel rotatably supported on said shaft, a ratchet connecting with said wheel, a pawl on said shaft to actuate the ratchet and to form therewith a one way driving connection between said shaft and 20 said wheel, means including an actuating pawl to engage said ratchet, a spring to operate said actuating pawl to feed the carriage, and means operable by the key levers to effect the restoration of said pawl to normal against the action of said spring.

FRANK SPALOSS.
